US00D598433S

(12) **United States Design Patent**
Schneider et al.

(10) **Patent No.:** **US D598,433 S**
(45) **Date of Patent:** **** Aug. 18, 2009**

(54) **TAPERED LOOP ANTENNA ELEMENT**

(75) Inventors: **Richard E. Schneider**, Wildwood, MO (US); **John Edwin Ross, III**, Salt Lake City, UT (US)

(73) Assignee: **Antennas Direct, Inc.**, Eureka, MO (US)

(**) Term: **14 Years**

(21) Appl. No.: **29/304,423**

(22) Filed: **Feb. 29, 2008**

(57) **CLAIM**

The ornamental design for a tapered loop antenna element, as shown and described.

DESCRIPTION

FIG. 1 is a perspective view of the tapered loop antenna element, showing our new design;

FIG. 2 is a front elevation view thereof;

FIG. 3 is a back elevation thereof;

FIG. 4 is a bottom plan view thereof;

FIG. 5 is a top plan view thereof;

FIG. 6 is a right elevation view thereof;

FIG. 7 is a left elevation view thereof; and,

FIG. 8 is an exploded perspective view thereof in use.

In the drawings, the broken lines depict environmental subject matter only and form no part of the claimed design.
